UNITED STATES PATENT OFFICE

RALPH E. FLANDERS, OF SPRINGFIELD, VERMONT, ASSIGNOR TO JONES & LAMSON MACHINE COMPANY, OF SPRINGFIELD, VERMONT, A CORPORATION OF VERMONT

GRINDING MACHINE

Application filed May 27, 1922, Serial No. 564,091. Renewed March 6, 1929.

This invention relates to grinding machines, having been particularly designed for grinding the threaded faces of taps. Taps are fluted longitudinally to form cutting edges with the sides of the threads and in order to cut properly it is desirable to form the threaded portions of less diameter back from the cutting edges at the flutes in order to give clearance for these cutting edges. For this purpose this invention provides means for automatically increasing and decreasing the depth of cut on the threaded faces in proper relation to the flutes to provide a proper backing off or clearance for the cutting edges of the tap.

Another feature of this invention relates to the truing devices for insuring that the grinding is effected to the desired contour.

A further feature of the invention relates to mechanism by which correct sizing of the taps is insured automatically regardless of the amount of truing imparted to the grinding wheel during the grinding on each tap or in operating on successive taps, and means by which the amount of truing in each instance may be adjustably determined.

Further objects and advantageous details and combinations of parts will appear from a more complete description of one embodiment of the invention shown in the accompanying drawings in which

Figure 1 is a front elevation of the machine.

Figure 2 is a left side elevation.

Figure 3 is a right side elevation.

Figure 12 is a fragmentary right-hand elevation similar to a portion of Figure 3, but drawn to a larger scale.

Figure 13 is a fragmentary view partly in section of a modified form of truing mechanism.

Figure 14 is a section on the line 14—14 of Figure 13.

Figure 15 is a fragmentary section illustrating a modified form of tap-relieving mechanism.

Figure 16 is a sectional detail through a knock-off mechanism.

This machine in general comprises means for supporting a tap between centers and rotating the tap, means for supporting and driving a grinding wheel in operative relation to the tap, means for effecting a traverse longitudinally of the tap between the wheel and the tap, means for effecting a relative movement between the tap and the wheel to back off or relieve the tap from its cutting edges, wheel-truing devices, and means for actuating the truing devices in such manner that the contour of the wheel is maintained correct and so that the tap may be ground to correct finished size.

80

Work supporting and actuating mechanism

In the machine shown a base 1 is employed to support the various mechanisms and for the purpose of supporting the work-holding centers may be provided on its upper forward face with a pair of guides 2 for slidably supporting a traversing carriage 3. While as shown the traversing carriage slides, it might be otherwise supported with capability of traversing movement in any suitable way. Depending from the carriage 3 between the guides 2 is shown a bracket 4 (see Figure 5) having journaled therein at its lower end a cam follower roll 5 bearing against an edge 6. This edge cam is carried by a drum 7 journaled on a vertical stub shaft 8 fixed in the machine base. The edge cam 6 acting on the roll 5 causes traversing movements of the carriage in one direction, while the return

85

90

95

100

movement is effected by means of a tension spring 10 fixed at its outer end to a bracket 11 depending from the carriage, passing through an opening 12 in the base 1, and made fast inside this base to a pin 13 fixed in position thereon. This spring serves to urge the cam follower 5 against the cam 6. The traversing motion of the carriage may be limited in one direction by means of an 10 adjusting screw 14 threaded through the bracket 11 and impinging on a portion of the base 1.

The carriage 3 carries the head and tail stocks for supporting the tap. As shown 15 the head stock comprises a sleeve 20 adjustable longitudinally within a bearing 21 projecting upwardly from one end of the carriage. This adjustment may be effected by means of a toothed stud 22 journaled in the 20 bearing 21, the teeth of which mesh with rack teeth 23 formed in the sleeve 20. Forwardly of the bearing 21 this stud 22 may be provided with a head 24 by which it may be turned to adjust the sleeve and suitable clamping bolts 25 may be employed to fix the sleeve 20 in adjusted position, this method of adjusting and clamping being well known in the art.

Slidable within the sleeve 20 is a center 30. 30 This center may be supported in any suitable way, one method well known in the art being shown in which the center has slidable in a socket in its rear end a pin 31 urged outwardly therefrom by means of a spring 32. 35 This pin impinges on the inner face of a cap 33 made fast by threaded or other suitable connections to the outer end of the sleeve 20. By this means the center 30 is urged away from the cap 33 as far as is permitted by the 40 engagement of rack teeth 34 thereon with a segment 35 fixed to a vertical shaft 36 which has an operating handle 37 at its upper end above the cap 33. This spring 32 prevents lost motion between the rack and segment. 45 The inner end of the sleeve 20 may carry a face plate 40 having fixed thereto an outwardly extending arm 41 for engagement with a dog or other suitable device, as shown in Figure 8 clamped to the cap T placed 50 between the centers. This face plate is rotated, this being effected, as shown, by means of a gear portion 42 formed on the face plate with which meshes a pinion 43 fixed to a shaft 44 journaled in parallel relation to the 55 center 30. This shaft 44 is journaled in a sleeve 45 fixed to move with the sleeve 20 and slidable through a portion of bearing 21 and is also journaled in a sleeve 46 also slidable through one wall of the bearing 21. 60 Between the sleeves 45 and 46 shaft 44 has fixed thereon a gear 47 which meshes with a long gear 48 keyed to a shaft 49 which extends the length of the carriage 3. The gear 48 is of sufficient length to permit the mesh- 65 ing of the gear 47 therewith throughout the

range of axial movement of the sleeve 20. The shaft 49 has fixed thereon a long gear 50 by which it may be rotated in a manner to be later described.

The tailstock, positioned opposite the headstock in the usual manner, comprises a sleeve 60 similar to the sleeve 20 and slidable axially through a bearing 61 in which it is adjustable by means of a toothed stud 62 constructed in a similar manner to the stud 22. The stud 62 may be turned by means of a bolt head 64 (see Figure 1) and may be fixed in adjusted position by clamping bolts 65 in the same manner as the sleeve 20 of the headstock. The sleeve 60 has passing therethrough a center 70. The inner end of this center terminates in the usual cone point 71 and back of this point it has fixed thereto a bearing block 72 having a spherical shaped bearing face seated within a mating socket plate 73 bolted through mating flanges 74 and 75 to the inner end of the sleeve 60, the flange 75 being preferably formed integral with this sleeve. This mounting of the inner end of the tailstock center permits a universal pivotal or gyratory motion of this center and forms one construction for effecting the relieving action for the cutting edges of the tap, as will be described.

The rear end of the center 70 is of reduced diameter and passes through a central opening in a sleeve 76 journaled within the outer end of the sleeve 60. The outer end of this sleeve has fixed or integral therewith a gear 77 which bears closely against the outer end of the sleeve 60. This portion of the mechanism is shown to an enlarged scale in Figure 11. Adjacent this gear 77 the sleeve 60 is shown of reduced diameter and carries positioned thereon a depending bracket arm 78 which is employed to carry certain of the driving mechanism for effecting the gyratory motion of the center in a manner which will be described. This bracket 78 is fixed against a shoulder 79 formed by the reduced portion of the sleeve 60, by means of a collar 80 threaded over the outer threaded end of this sleeve 60 and bearing hard against the bracket. The gear 77 is recessed on its outer face to form a pair of parallel guideways 85 in which is movable a slide 86, this slide being adjustable across the axis of the gear 77 (Figures 11 and 12). This slide has a central circular opening 87 therein and within this opening is positioned a collar 88 having its outer edge formed spherical, this collar being fixed to the center 70. By adjusting the slide 86 so as to position the opening 87 out of the axis of the gear 77, rotation imparted to the gear 77 causes a circular bodily movement to be imparted to the collar 88 to effect a gyratory motion of the center 70, this center not revolving about its own axis. The position of the slide 86 may be fixed by means of tightening screws 89 passing through slots 130

89^a therein and in order to show the adjustment effected a scale may be marked on one of the guideways 85 cooperating with an index mark on the slide to indicate the amount by 5 which the collar 88 is moved off center with relation to the axis of the gear 77. A cover plate 90 is positioned against the outer face of the slide 86 to carry the screws 89 and against this cover plate bears a washer 91 10 which is urged inwardly against the cover plate by means of a spring 92 surrounding the reduced portion 93 of a knurled adjusting knob 94 threaded on the outer end of the center 70.

15 The gyratory motion of the cone point 71 will be of much smaller amplitude than that of the collar 88, due to the lengths of the lever arms of these two elements from the center of motion determined by the block 72 and its 20 socket plate 73. This motion, however, is imparted to the end of the tap, the shank end of which is preferably carried by the center 30, so as to cause a movement of the tap toward and from the grinding wheel as 25 will be described later. This motion of the center must be timed with relation to the rotation of the tap and the number of flutes thereon, so as to cause the cutting to be deeper back from the cutting edges of the tap than at 30 its cutting edges to produce proper clearance for the tap in operation. For this purpose this motion of the tailstock center is effected preferably by gearing from the tap-rotating mechanism. In the present embodiment this 35 gearing comprises a sleeve 100 journaled in the bracket 78 and slidably keyed to the reduced extremity 101 of the shaft 49. This sleeve 100 has clamped thereon by means of a threaded clamping collar 102, a gear 103 which 40 meshes with a gear 104 carried by a stub shaft 105 adjustable in an arcuate slot 106 in the bearing 78 having as its center the axis of the gear 77. The shaft 105 also carries a gear 107 which meshes with the gear 77. By selecting a gear 103 of the proper size the correct number of rotations of the gear 77 to produce the proper number of gyratory movements of the center 70 in time with the rotation of the tap and properly related to 45 the flutes of the tap may be effected.

Another method of effecting a suitable relieving movement to the center is illustrated in Figure 15, in which, instead of producing a gyratory movement to the center, a pivotal motion is imparted thereto about an axis perpendicular to that plane which passes through the axis of the tap and the central point of action therewith of the grinding wheel. Referring to this Figure the inner 55 end of the sleeve 60^a has fixed thereto a cap or headpiece 110 through which passes a pivot 111 forming an axis about which the center 70^a is pivoted. The pivot 111 is vertical in the present embodiment since the grinding wheel acts on one side of the work in a horizontal plane containing the axis thereof. The stub shaft 105, in this form of mechanism, has journaled thereon a member comprising a gear 112 which takes the place of the gear 104 of the form previously described 70 and which meshes with the gear 103. Formed integral with or fixed to the gear 112 is an eccentric 113 preferably having its eccentric face spherical to permit a slight universal movement thereon of an eccentric 75 strap 114. The outer end of this eccentric strap is pivoted at 115 to the outer end of the center 70^a. On rotation of the gear 112, therefore, it is evident that rocking movement is imparted to the center about the pivot 111 to move the work toward and from the grinding wheel, the amount of such motion depending on the throw of the eccentric 113 and the timing of this throw being dependent on the setting and size of the 80 change gear 103. While as shown the relieving motion is imparted only to the tailstock center, it is regarded as within the scope of this invention to impart a similar relieving motion to the headstock center, if 85 desired, and to time the relieving motions either together or one motion lagging the other to conform to any conditions which may be met in practice when working on either straight or spirally fluted taps. 95

Grinder wheel mounting

Mounted in cooperative relation to the head and tailstock support or carriage is a grinding wheel having its edge shaped to 100 grind the threaded faces of the tap. This wheel may be mounted in any suitable manner to effect the desired results, but as shown is carried by a shaft 150 (see Figures 1, 8, and 9) which is journaled in bearings 151 105 carried by a plate 152. This plate has a circular extension 153 which is journaled in a circular opening in the end of a drum-shaped casing 154 by which means the angular position of the shaft 150 may be adjusted by a 110 rotary adjustment of the portion 152 with relation to the drum. The grinding wheel 155 is carried by the shaft 150 diametrically with relation to the portion 153 and extends through a slot 156 therein as best shown in 115 Figures 8, 9, and 10. The plate 152 may be adjusted angularly, as above described, and fixed in position relative to the casing 154 by means of clamping bolts 157 passing through the circular portion 153 and engaging in clamping blocks 158 on the rear side of the plate bridging over the joint between the circular portion 153 and the casing 154. This angular adjustment is for the purpose of enabling the line of cutting action of the 120 wheel to be adjusted in accordance with the pitch of the tap thread. The casing 154 is formed on the end of a carriage 160 which may be mounted in any suitable manner permitting the wheel and the work to be given 125 130

a relative feeding movement. In the present embodiment this is effected by forming the carriage 160 as a slide movable on the base 1 at right angles to the movement of the work carriage 3 and toward and from the path of movement thereof. By this construction the grinding wheel is properly presented to the work and by sliding the carriage 160 feed and retractive motions may be imparted thereto in proper time with a traversing movement of the carriage 3 which supports the tap.

For the purpose of driving the grinding wheel the rear end of this carriage 160 has fixed thereon a cradle 162 on which is pivoted, by a pintle 163, the axis of which is in alignment with the axis of the disk portion 153, a motor support 164 carrying thereon a motor 165. The drive pulley 166 of this motor is belt connected by a belt 167 through an opening 168 in the plate 152 with a belt pulley 169 keyed to the shaft 150. The pivotal mounting of the motor is provided to permit its axis to be adjusted parallel to the axis of the shaft 150, or as nearly parallel as is necessary to secure proper driving effect on this shaft.

In order to avoid the necessity of reversing the direction of rotation of the tap on a reverse direction of traverse, this reverse direction is made idle and for this purpose it is necessary to withdraw and so hold the grinding wheel while this traverse is taking place. For this purpose the following mechanism has been provided. Referring to Figures 4 and 6, the base 1 beneath the carriage 160 is provided with a bracket 180 having its upper end formed as a sleeve 181. Slidable through this sleeve is a plunger 182 which is prevented from rotation relative to this sleeve by a lug 183 depending from one end thereof and engaging between guide ribs 184 formed on the machine base 1. This plunger 182 is hollow and one end is threaded through a portion of its length as shown at 185. In engagement with the threads of this portion is a screw 186 formed on a shaft 187. This shaft is journaled in a lug 188 extending downwardly from the carriage 160 and is prevented from axial movement relative thereto by means of a thrust member 189^a, which may be formed either as a sleeve fixed to the shaft 187, or it may be made integral therewith, which bears on one side of the lug 188, and a gear 190 fixed to the shaft on the opposite end of the lug 188. With this construction it is evident that movement imparted to the plunger 182 acts to move the slide 160 to impart feed and retractive motions to the wheel, and also that the relative positions of the carriage 160 and the plunger 182 may be adjusted by rotation of the shaft 182. Movement of the plunger 182 is effected to withdraw the wheel from cutting engagement with the work by means of a cam member 195 (see Figures 5, 6, and 7) ad-

justably fixed to the periphery of the cam drum 7, above mentioned, which acts at certain times to impinge against a bell crank follower arm 196 (see Figures 4, 6, and 7) the outer end 197 of which (see Figure 4) engages in a notch 198 in the inner end of the plunger. The slide 160 is normally urged to the inward cutting position of the wheel by means of a tension spring 200 fixed at one end to a lug 201 depending from the slide 160 and at its opposite end to a portion of the bed 1. The forward limit of motion of the plunger is determined by means of a stop 202 formed as a pin seated within an upstanding wall member of the machine base.

As before stated the relative positions of the slide 160 and the plunger 182 may be adjusted by rotation of the shaft 185. For the purpose of effecting this rotation the sleeve portion 189 has keyed thereon a gear 205 which meshes with an elongated gear 206 fixed to or integral with a feed shaft 207 journaled in the machine base 1 and extending through the forward face thereof where it has fixed thereto a gear 208 and beyond this gear a hand wheel 209. Hand feeding may be effected by rotation of the hand wheel 209 and there is also a power feed mechanism which acts through the gear 208. This power feed mechanism is driven in proper time relation to the work traverse by means of mechanism shown more particularly in Figures 1, 2, 3, and 8. As shown in these figures a cam plate 220 is adjustably fixed to the outer face of the cam drum 7 and is adapted to impinge at certain times on a follower roll 221 carried by an arm 222 fixed to a rock shaft 223. Forwardly of the machine base this rock shaft carries a bell crank lever 224 to the upper end of which is pivoted a link 225 which extends downwardly and is pivoted at its lower end at 226 to the lower end of an arm 227 journaled on a stub shaft 228. The upper end of this arm 227 is normally urged to the right, as shown in Figure 1, by means of a spring 229 engaging at one end a pin 230 on the arm 227 and at the other end a pin 231 extending outwardly from the machine base. The upper end of this arm 227 has pivoted thereto a gravity actuated pawl 235 adapted to engage in ratchet teeth 236 of a wheel 237 journaled on the stub shaft 228. Fixed to rotate with this wheel is a pinion 239 which meshes with the teeth of the gear 208 on the feed shaft. By rocking motion imparted to the arm 227 it is therefore evident that the feed shaft may be rotated to turn the screw shaft 186, above mentioned, to impart feed motion to the grinding wheel. The extent of feed motion at each actuation of arm 227 is adjustable, this being determined by a stop comprising a bolt 240 having a knurled head 241 and extending through a threaded boss 242 projecting from the front face of the base 1, the end of which bolt is engaged by 130

the lower arm 243 of the bell crank lever 224. Adjustment of this bolt determines one limit of rocking movement of the rock shaft 223 and therefore determines the length of stroke imparted to the arm 227 by the cam block 220. 5 The abutment screw 241 may be fixed in adjusted position by a knurled lock nut 244 threaded thereon.

It is also desirable to limit the total extent 10 of feed motion imparted by the automatic feed mechanism. For this purpose a pawl knock-off may be employed, as shown this comprising an arm 250 journaled on the stub shaft 228 and having a knock-off cam portion 15 251 which is adapted to move beneath a portion of the pawl 235 and lift it from engagement with the teeth 236. This arm 250 may be adjustably positioned angularly with relation to the wheel 237 and for this purpose 20 the wheel 237 is provided with a rim having internal gear teeth cut therein, as shown at 252, with which may engage a pinion rotatably by turning a knob 255 fixed thereto. A spring-pressed plunger 253 seated 25 in a socket 254 in the arm 250 engages ratchet teeth on the knob 255 and acts to yieldingly hold the pinion in any angular position to which it may be turned. It is evident that 30 turning of this pinion changes the angular setting of the arm 250 relative to the wheel 237. The plunger also permits the amount of turning to be evident to the operator who may readily feel the movement of each ratchet tooth. With this construction, after sufficient 35 feed movement has taken place to bring the release cam 251 in engagement with the pawl 235, the latter is raised from engagement with the teeth 236 and further movement of the arm 227 of the cam 220 becomes ineffective to 40 impart feed movement to the wheel.

Truing mechanism

In order to produce accurate work it is necessary that the cutting faces of the grinding wheel be trued. For this purpose novel truing mechanism has been provided which is also designed so that when the threaded faces of the tap have been ground to the proper size any further relative feeding motion between the tap and grinding wheel 45 will be ineffective to cut deeper since a corresponding equal movement of the truing devices or tools is produced to remove the cutting faces of the wheel at the same rate as 50 the feeding movement. One embodiment of the truing mechanism is shown in Figures 4, 8, and 9 in which the devices are shown as carried on a slide 270 mounted in guides on the upper face of the slide 160 and moving 55 parallel to the direction of motion of this slide. The truing mechanism, therefore, moves with the carriage 160 and is also capable of being moved independently thereof. This is effected by means of a screw 271 60 formed on the end of a shaft 272, the threads

engaging in a lug 273 depending from the slide 270. The shaft 272 is journaled in a bearing boss 274 upstanding from the rear end of the carriage 160 and is prevented from moving axially relatively thereto by an enlarged portion or sleeve 275 fixed to or integral therewith bearing on one side of the boss 274, and a sleeve 276 journaled on this shaft 272 bearing on the opposite side of the boss 274. The sleeve 276 has a flange 277 thereon which is formed as a gear and meshes with the teeth of gear 190. The outer end of the sleeve 276 has a disk-shaped flange 278 thereon with which engages frictionally a disk 279 keyed to the outer end of the shaft 272 and adapted to be clamped against the flange 278 by means of a nut 280 threaded on the outer end of the shaft and engaging a bearing washer 281 impinging on the outer face of a disk 279. A handle 282 is also fixed to the disk 279 by which it may be turned, when the nut 280 has been loosened, to impart rotation to the shaft 272 independent of rotation imparted thereto through the gear 277. By this means, when the nut 280 has been tightened, motion imparted to the gear 190 through the feed shaft 207 also imparts a feed motion to the slide 270. The screws 271 and 186 are of equal pitch so that feed motion 65 imparted to the slide 160 when the nut 280 is clamped in position imparts an additional movement of the slide 270 relative to the carriage 160 in the same direction and of equal amount. The relative positions of the slide 270 and the carriage 160 with relation to the work may be changed by loosening the nut 280 and manipulating the handle 282. 90

As before stated, the slide 270 carries the truing mechanism and for this purpose it is provided with a segmental-shaped casing portion 290 formed with spaced inner and outer concentric vertical walls 291 and 292, end walls and a cover plate 293 bridging the top thereof. Centrally disposed through the walls 291 and 292 in the plane of the grinding wheel is a rock shaft 294 and between the walls 291 and 292 preventing axial movement of this shaft, except as they may be relatively adjusted, is a beveled gear 295 fixed thereto. At either side of this gear are fixed 105 angularly disposed stub shafts 296, one only of which is shown in Figure 9, which carry similar bevel gears 297 meshing with the gear 295. These gears 297 in turn mesh with similar bevel gears 298 fixed to shafts 299 which are journaled in the walls 291 and 292 and extend toward opposite beveled side cutting faces of the grinding wheel where this wheel 110 extends rearwardly of the plate 152. Each of the shafts 294 and 299 at their inner ends 115 have upwardly extending portions 300 in which are adjustably fixed diamonds or other suitable truing tools 301. These truing devices or tools are offset from the axes of their respective shafts, so that by rocking 120

70

85

90

95

100

105

110

115

120

125

130

these shafts it is evident that the tools are moved in arc-shaped paths, each path being in a plane, the two side tools operating in the planes of the angularly disposed side cutting faces of the grinding wheel and the central tool acting perpendicularly to the central plane of the wheel. The side tools therefore serve to true the side faces of the wheel and the center tool serves to true the apex. The tools are designed to act on the wheel at points diametrically opposite to the action of the wheel on the work, and while the rocking motion imparted thereto to cause the tools to traverse the entire width of the cutting faces of the wheel brings them slightly out of this plane, the deviation therefrom is so slight as to be negligible. The rocking of the tools to effect their truing strokes is effected by means of a cam element 310 adjustably fixed to the cam drum 7, before referred to, which acts on a cam roll 311 carried by a bent lever 312 (Figs. 2, 6 and 7) which passes out through a side wall of the base 1 through an opening 313, where it has formed thereon a sleeve portion 314 journaled on a vertical pivot 315. Extending outwardly from the sleeve 314 is an arm 316 to the end of which is adjustably fixed an abutment screw 317 acting to limit the inward movement of the arm, this arm normally being held toward this limit of motion by a spring 318 engaging a perforated lug 319 thereon at one end and extending into the casing 1 and attached to a fixed point therein at the other end. The upper portion of the sleeve 314 has fixed thereto an upwardly inclined arm 320 having a horizontally perforated boss 321 at its upper end. Through this boss passes a pivot bolt 322 to which is pivoted by a vertical pin 323 a link 324 (Figures 8 and 9). The inner end of this link is pivoted by a horizontal pivot bolt 325 to the upper end of an arm 326, the lower end of which is made fast to the outer end of the shaft 294. It is therefore evident that as the cam drum rotates the arm 321 is rocked periodically and rocking motion imparted by the connections above described to the shaft 294 and through the bevel gears to the shafts 299, thus imparting truing motion to each of the truing devices.

A modified form of mechanism for imparting rocking motion to the truing device shafts and for adjusting the relative positions of the truing devices is shown in Figures 13 and 14. Referring to these figures the truing tools 301 are adjustably mounted in the ends of the centrally disposed rock shaft 294 journaled in the walls 291 and 292 of the segmental-shaped portion of the slide 270 and in shafts 330 positioned on opposite sides of the central shaft and inclined relative thereto to act on the lateral cutting faces of the wheel in the same manner as described in connection with the first form. Each shaft 330, however, instead of being journaled di-

rectly in the wall 292 is journaled in a bushing 331 seated in an opening therein and having a flange 332 at its inner end to prevent it from being removed outwardly through the opening in the wall 292. Through the rear end of each bushing 331 is threaded an adjusting screw 334 which bears at its inner end against the rear end of the corresponding shaft 330. By adjustment of these screws the endwise positions of the shafts 330 may be adjusted. A set screw 335 may be employed to lock each adjusting screw 334 in adjusted position. Within the bushing 331 each shaft 330 is threaded as shown at 336, and screwed thereon is a collar 337. This collar abuts against the rear end of a sleeve 338 which is slidably keyed to the shaft 330 and which is urged against the collar 337 by means of a coil spring 339 surrounding a portion of the sleeve 338 and bearing at one end against the inner face of the wall 291 and at the other end against a shoulder 340 on the sleeve 338. By the pressure exerted on the collar 337 by this spring each shaft 330 is urged into engagement with the end of its adjusting screw 334. Each collar 338 has formed thereon a gear segment 341 which meshes with rack teeth 342 on a segmental rack bar or face gear 343 which is mounted for limited sliding movement beneath the cover plate 293. This segmental rack bar meshes with the gear segments 341 on each shaft 330 and also meshes with a similar segment, not shown, fixed to the rock shaft 294. By this construction it is evident that rocking motion of the rock shaft 294 may be transmitted through the gear segment thereon to the segmental rack bar 343 and is imparted from this rack bar through the segmental bars 341 to the rock shafts 330 to impart truing movement to the truing devices 301 carried thereby. Adjustment of the collar 337 permits the position of the gear segment 341 axially of each rock shaft 330 to be adjusted in conformity to the axial adjustment of this rock shaft by means of the adjusting screw 334. The rack bar 343 may be guided so as to be moved in an arcuate path by guide pins threaded in the cover plate 293 and projecting through slots in the rack bar or by guide slots cut in the transverse vertical walls connecting the walls 291 and 292.

Driving mechanism

Reference has been made above to the shaft 49 from which is derived the rotating and back-off or clearance producing motions for the tap, and also to a cam drum 7 by which traversing movement is imparted to the work-supporting carriage 3, reTRACTING motion of the grinder wheel for the idle traverse of the work-supporting carriage is effected as well as the actuating of the feed mechanism, and the truing movement of the wheel-tru- 130

ing mechanism. These members are driven in the following manner. Referring more particularly to Figures 2 and 3, at 350 is shown an electric motor bolted to the rear vertical wall of the machine base 1. The drive pulley of this motor being shown at 351 is belt-connected to a drive pulley 352 carried by a main power shaft 353. This shaft 353 extends through a suitable bearing in the outer wall of the base 1 and inwardly of this bearing is fixed thereto a pinion 354, as shown in Figures 4, 5, and 7. This pinion meshes with a gear 355 journaled on a shaft 356 and fixed to rotate with the gear 355 is a pinion 357. This pinion meshes with a gear 358 journaled on a shaft 359. One face of the gear 358 carries clutch elements 360 and mating with these elements are clutch elements 361 of a collar 362 slidably keyed to the shaft 359. The collar 361 is grooved for the reception of jaws 363 at the end of an arm 364 (shown in dotted lines in Figure 1), which is fixed to a rock shaft 365. This rock shaft extends through the front wall of the machine bed 1 and outwardly thereof has fixed an actuating lever 366 terminating in a handle 367. By the actuation of this handle the rock shaft 365 may be manipulated to clutch or unclutch the gear 358 to the shaft 359. Keyed to the shaft 359 is a gear 368 which meshes with a gear 369 on a stub shaft 370. This gear 369 meshes in the long gear 50, above mentioned, which is fixed to the shaft 49.

Outwardly of the frame member 1 the shaft 359 has fixed thereto a gear 375 with which meshes a gear 376 fixed to a shaft 377 which extends through journals 378 (see Figure 7) in the machine base 1 and carries on its opposite end a worm 379. This worm 379, as shown in Figures 1, 2, and 7, meshes with a worm wheel 380 formed integral with or attached to the lower portion of the cam drum 7. Through the mechanism just described the cam drum 7 and the work-rotating and relieving mechanism are driven, this drive being controlled through the clutch actuated by manipulation of the handle 367.

With the machine constructed as above described the cycle of operations may, if desired, be as follows. A working traverse of the tap may be effected in one direction past the grinding wheel, the truing devices at that time being out of operative position and the tap being moved toward and from the wheel in time with its rotation and traverse to properly form the threaded faces thereof with clearance from the cutting edges of the tap at one side of each flute. At the end of this traverse a slight dwell in the traversing motion may occur and a feed motion is then imparted to the grinding wheel and a motion of the same amplitude to the truing mechanism. The grinding wheel and truing mechanism together are then retracted from cutting position, and the return traverse of the work carriage effected and if desired at a higher rate of speed than the working traverse. During the idle traverse the truing devices may be caused to pass across the faces of the grinding wheel to contact therewith or not depending on the relative setting of the mechanism. At the end of the idle traverse the wheel is again moved into its operative position which will be further toward the work than on the previous working traverse by the amount of the feed motion given at the end of the previous working traverse. The cycle of operations is then repeated until the work is finished. The machine should be set, however, so that prior to the automatic throwing out of the feed by the pawl knock-off, the truing devices shall have engaged an effected a truing action on the grinding wheel so that the final cutting strokes shall be made by the wheel dressed to the proper form and fed to the required depth for the diameter of the tap desired. Attention is called to the fact that after the completion of work on a single tap, should another tap be operated upon without changing the setting of the pawl knock-off mechanism, the truing devices would not become operative on the wheel and consequently the finished work would be incorrect in shape to the extent to which the wheel had become misformed in the grinding of the tap and would be over sized to the extent of the wear on the wheel. It is therefore important that this pawl knock-off mechanism should be set back somewhat for each grinding operation so that the tap operated upon will be reduced to accurate shape and size when the feed has automatically ceased.

Another cycle of operations possible with this machine may be effected by providing a lead cam 6 having a pair of spaced high portions to effect two complete traverses on each rotation of the cam. The truing mechanism cam may then be positioned so as to give a single oscillation of each truing device after the first operative traverse and to give a reverse motion to the truing devices after the second operative traverse, thus giving a single truing stroke between each operative traverse of the work instead of two truing strokes as in the previously described cycle, thus permitting the time for the return idle traverse to be shortened and so somewhat increase the speed of the machine. Other cycles of operation, of course, could be provided by changing the forms of the cams on the cam drum 7 and adjusting them variously angularly relative thereto.

While as shown the machine is designed for operating on taps, it is evident that many of the features of the invention are applicable to the making of reamers, hobs and other devices, such modifications as might be found necessary or desirable being made to adapt the machine to the particular surface desired.

For example, for grinding reamers a flat faced grinding wheel would be used in place of the angular faced wheel shown.

Having thus described certain embodiments of this invention it should be evident to those skilled in the art that they are merely illustrative and that many changes and modifications might be made therein without departing from the spirit or scope of the invention as defined by the appended claims.

I claim:

1. In a machine of the class described, a tool, centers for supporting a fluted cutting member in operative relation to said tool, one of said centers having a universal pivotal mounting intermediate its length, means to rotate said tap, and means to effect a gyratory movement of said center timed with the rotation of said cutting member and acting to effect a larger diameter cut thereon as the point of action of said tool approaches the cutting faces of said tap to effect clearance for said faces when in use.
2. In a machine of the class described, a pair of centers between which work may be supported, one of said centers having a bearing member intermediate its length having a spherical surface, a socket for receiving said bearing member, a sleeve through which said center extends and to one end of which said socket is made fast, a second sleeve journaled in the opposite end of said first-mentioned sleeve and through which said center passes, a slide adjustable diametrically across the second sleeve, a collar on said center having a spherical face journaled in said slide, and means for rotating said second sleeve to cause a gyratory movement of said center depending in amplitude on the adjustment of said slide relative to said second sleeve.
3. In a machine of the class described, a pair of centers between which work may be supported, one of said centers having a bearing member intermediate its length having a spherical surface, a socket for receiving said bearing member, a sleeve through which said center extends and to one end of which said socket is made fast, a second sleeve journaled in the opposite end of said first-mentioned sleeve and through which said center passes, a slide adjustable diametrically across said second sleeve, a collar on said center having a spherical face journaled in said slide, means for rotating said second sleeve to cause a gyratory movement of said center depending in amplitude on the adjustment of said slide relative to said second sleeve, and means for adjusting said centers toward and from each other.
4. In a machine of the class described, a tool, means for supporting work in operative relation to said tool, means for effecting a relative traverse between said tool and the work, means for moving said tool and work apart to cause an idle traverse in one direc-

tion and to return said tool and work to operative position for the opposite direction of traverse, means for effecting a relative feed between said tool and work, tool-truing mechanism, and means for effecting a relative feed between said tool and mechanism of equal amount to that between said tool and work to determine the final size of the work by the relative initial settings of the work and truing mechanisms while permitting the tool to be trued by variable amounts.

5. In a machine of the class described, a tool, means for supporting work in operative relation to said tool, means for effecting a relative traverse between said tool and the work, means for moving said tool and work apart to cause an idle traverse in one direction and to return said tool and work to operative position for the opposite direction of traverse, means for effecting a relative feed between said tool and work, tool-truing mechanism, means for effecting a relative feed between said tool and mechanism of equal amount to that between said tool and work to determine the final size of the work by the relative initial settings of the work and truing mechanisms while permitting the tool to be trued by variable amounts, and means for predetermining the amount of truing when operating on each piece of work.

6. In a machine of the class described, a work holder, a support, a grinding wheel carried by said support in position to operate on work carried by said holder, a wheel-truing mechanism carried by said support and movable toward and from said wheel, means to move said carrier toward said work holder to impart relative feed movement between said wheel and work, means to move said mechanism on said support to impart relative feed between said mechanism and wheel, and means to couple said feed means so that said mechanism is moved against said wheel at the rate of feed movement between said wheel and work.

7. In a machine of the class described, means for rotatably supporting a tap, means for effecting an axial traversing movement of the tap, a grinding wheel movable into and out of cooperative relation to the tap, means for moving said wheel out of tap-cutting position for one direction of tap traverse and for moving said wheel into tap-cutting position for the opposite direction of traverse, means for effecting a feed movement of said wheel, wheel-truing mechanism, and means actuatable by said wheel-feeding means for feeding said mechanism to said wheel.

8. In a machine of the class described, means for rotatably supporting a tap, means for effecting axial traversing movement of the tap, a grinding wheel angularly adjustable to conform to the pitch of the tap threads and movable into and out of cooperative relation to the tap, means for moving said

- wheel out of tap-cutting position for one direction of tap traverse and for moving said wheel into tap-cutting position for the opposite direction of traverse, means for effecting 5 a feed movement of said wheel, wheel-truing mechanism, and means actuatable by said wheel-feeding means for feeding said mechanism to said wheel.
9. In a machine of the class described, a 10 work holder, a grinding wheel, means for effecting a relative feed between said wheel and work holder, wheel-truing mechanism, and means actuatable by said feed means for feeding said mechanism toward said wheel.
- 15 10. In a machine of the class described, a work holder, a grinding wheel, means for effecting a relative feed between said wheel and work holder, wheel-truing mechanism, means actuatable by said feed means for feeding 20 said mechanism toward said wheel at an equal rate to the feed between said wheel and work holder, and means for adjustably limiting the extent of feed.
11. In a machine of the class described, a 25 work holder, a grinding wheel, means for feeding said wheel toward said work holder, wheel-truing mechanism movable with said wheel, and means actuatable by said feeding means to effect a relative feed between said 30 mechanism and wheel at an equal rate to the feed of said wheel toward said work holder.
12. In a machine of the class described, a 35 work holder, a grinding wheel, a wheel-truing mechanism, means for effecting a relative feed between said wheel and work holder, means for effecting a relative feed between said wheel and mechanism so related to the feed between said wheel and work holder as to define a limit of effective cutting 40 depth movement by the truing of said wheel, and means for rendering said feed inoperative after a predetermined extent of truing has been effected.
13. In a machine of the class described, 45 a work carriage, a grinding wheel, wheel-truing mechanism, means to rotate work on said carriage, means to effect a relative traverse of said carriage and wheel to cut the work during one direction of traverse, means 50 to impart a relative feeding movement between said wheel and work at the end of each working traverse, means to impart a relative feed movement of said truing mechanism and wheel, means to impart a relative withdrawing motion between said wheel and work prior to the return traverse to cause said return to be idle, means for actuating said truing mechanism during said idle return traverse, and means for presenting said wheel 55 and work into work-cutting position prior to a succeeding traverse.
14. In a machine of the class described, a 60 work carriage, a grinding wheel, wheel-truing mechanism, means to rotate work on said carriage, means to effect a relative traverse 65 of said carriage and wheel to cut the work during one direction of traverse, means to effect a periodic relative approach and recession between said wheel and work during the rotation of said work, means to impart a relative feeding movement between said wheel and work at the end of each working traverse, means to impart a relative feed movement of said truing mechanism and wheel, means to impart a relative withdrawing motion between said wheel and work prior to the return traverse to cause said return to be idle, means for actuating said truing mechanism during said idle return traverse, and means for presenting said wheel and work into work-cutting position prior to a succeeding 70 traverse.
15. In a machine of the class described, a 75 work carriage, a grinding wheel, wheel-truing mechanism, means to rotate work on said carriage, means to effect a relative traverse of said carriage and wheel to cut the work during one direction of traverse, means to impart a relative feed movement of said truing mechanism and wheel of equal magnitude to said relative work and wheel feed, means to impart a relative withdrawing motion between said wheel and work prior to the return traverse to cause said return to be idle, means for actuating said truing mechanism during said idle return traverse, and means for presenting said wheel and work into work-cutting position prior to a succeeding 80 traverse.
16. In a machine of the class described, a 85 work carriage, a grinding wheel, wheel-truing mechanism, means to rotate work on said carriage, means to effect a relative traverse of said carriage and wheel to cut the work during one direction of traverse, means to impart a relative feed movement of said truing mechanism and wheel, means to impart a relative withdrawing motion between said wheel and work prior to the return traverse to cause said return to be idle, means for actuating said truing mechanism during said idle return traverse, and means for presenting said wheel and work into work-cutting position prior to a succeeding 90 traverse.
17. In a machine of the class described, a 95 work carriage, a grinding wheel, wheel-truing mechanism, means to rotate work on said carriage, means to effect a relative traverse of said carriage and wheel to cut the work during one direction of traverse, means to effect a periodic relative approach and recession between said wheel and work during the rotation of said work, means to impart a relative feeding movement between said wheel and work at the end of each working traverse, means to impart a relative feed movement of said truing mechanism and wheel, means to impart a relative withdrawing motion between said wheel and work prior to the return traverse to cause said return to be idle, means for actuating said truing mechanism during said idle return traverse, and means for presenting said wheel and work into work-cutting position prior to a succeeding 100 traverse.
18. In a machine of the class described, a 105 work carriage, a grinding wheel, wheel-truing mechanism, means to rotate work on said carriage, means to effect a relative traverse of said carriage and wheel to cut the work during one direction of traverse, means to effect a periodic relative approach and recession between said wheel and work during the rotation of said work, means to impart a relative feeding movement between said wheel and work at the end of each working traverse, means to impart a relative feed movement of said truing mechanism and wheel, means to impart a relative withdrawing motion between said wheel and work prior to the return traverse to cause said return to be idle, means for actuating said truing mechanism during said idle return traverse, and means for presenting said wheel and work into work-cutting position prior to a succeeding 110 traverse.
19. In a machine of the class described, a 115 work carriage, a grinding wheel, wheel-truing mechanism, means to rotate work on said carriage, means to effect a relative traverse of said carriage and wheel to cut the work during one direction of traverse, means to effect a periodic relative approach and recession between said wheel and work during the rotation of said work, means to impart a relative feeding movement between said wheel and work at the end of each working traverse, means to impart a relative feed movement of said truing mechanism and wheel, means to impart a relative withdrawing motion between said wheel and work prior to the return traverse to cause said return to be idle, means for actuating said truing mechanism during said idle return traverse, and means for presenting said wheel and work into work-cutting position prior to a succeeding 120 traverse.
20. In a machine of the class described, a 125 work carriage, a grinding wheel, wheel-truing mechanism, means to rotate work on said carriage, means to effect a relative traverse of said carriage and wheel to cut the work during one direction of traverse, means to effect a periodic relative approach and recession between said wheel and work during the rotation of said work, means to impart a relative feeding movement between said wheel and work at the end of each working traverse, means to impart a relative feed movement of said truing mechanism and wheel, means to impart a relative withdrawing motion between said wheel and work prior to the return traverse to cause said return to be idle, means for actuating said truing mechanism during said idle return traverse, and means for presenting said wheel and work into work-cutting position prior to a succeeding 130 traverse.

relative feeding movement between said wheel and work at the end of each working traverse, means to impart a relative feed movement of said truing mechanism and wheel of equal magnitude to said relative work and wheel feed, means to impart a relative withdrawing motion between said wheel and work prior to the return traverse to cause said return to be idle, means for actuating said truing mechanism during said idle return traverse, means for presenting said wheel and work into work-cutting position prior to a succeeding traverse.

18. In a machine of the class described, a work carriage, a grinding wheel, wheel truing mechanism, means to rotate work on said carriage, means to effect a relative traverse of said carriage and wheel to cut the work during one direction of traverse, means to effect a periodic relative approach and recession between said wheel and work during the rotation of said work, means to impart a relative feeding movement between said wheel and work at the end of each working traverse, means to impart a relative feed movement of said truing mechanism and wheel, means to impart a relative withdrawing motion between said wheel and work prior to the return traverse to cause said return to be idle, means for actuating said truing mechanism during said idle return traverse, means for presenting said wheel and work into work-cutting position prior to a succeeding traverse, and means acting to render said feeding means inoperative after a predetermined extent of feed.

In testimony whereof I have affixed my signature.

RALPH E. FLANDERS.
